C. F. LOFE.
KEG LINER AND CLEAT.
APPLICATION FILED NOV. 22, 1916.

1,226,346.

Patented May 15, 1917.

INVENTOR

Charles F. Lofe.

BY

W. H. Muller

ATTORNEY

UNITED STATES PATENT OFFICE.

CHARLES FRANCIS LOFE, OF PITTSBURGH, PENNSYLVANIA.

KEG LINER AND CLEAT.

1,226,346.

Specification of Letters Patent. Patented May 15, 1917.

Application filed November 22, 1916. Serial No. 132,841.

To all whom it may concern:

Be it known that I, CHARLES F. LOFE, residing at Pittsburgh, in the county of Allegheny and State of Pennsylvania, have invented certain new and useful Improvements in Keg Liners and Cleats, of which the following is a specification.

My invention relates to certain new and useful improvements in devices for retaining the heads of kegs in place without the necessity of the use of nails for the purpose.

In its general nature, the invention consists of a strap metal device adapted to cross the head of the keg and engage the head, the ends of the device being bent over the edges of the keg staves and held in place by the end loop that is usually nailed to the outside of the keg near the end of the keg.

In its more detail nature, the invention includes those novel features of construction, combination and arrangement of parts, all of which will be fully described and then be specifically pointed out in the appended claims, reference being had to the accompanying drawing, in which:

Figure 1 is a perspective view illustrating a keg with the invention applied.

Fig. 2 is a detail side elevation of the invention *per se*.

Fig. 3 is a detail side elevation, parts being broken away, illustrating the invention as applied to a keg.

Fig. 4 is a detail section on the line 4—4 on Fig. 1.

In the drawing in which like numerals of reference indicate like parts in all of the figures, 1 represents the keg which is provided with the usual head groove 2 in which the head 3 is fitted, the head 3 being usually held in place by nailing.

In order that the heads may be quickly secured in place in a firm and convenient manner so that the head of the keg may not be removed or become loosened in transit, I provide the device which constitutes my invention and which consists of a pair of metal straps 4, one of which is provided with stamped tongues 5 that pass through slots 6 in the other strap member and are clenched over the same as at 7 to hold the strap members together in crossed relation.

Each strap member has its ends provided with hook like portions 8 that fit over the ends 9 of the staves 1 and project downwardly as at 10 to lie beneath the hoop 11

which is driven down over the end of the keg and over the projecting portions 10 of the hooks 8, the projecting portions 10 being extended as at 12 so as to be susceptible of being bent up over the hoop 11, as clearly indicated in Figs. 1 and 3 of the drawing, the hoop 11 being fastened in place by the usual nails 13.

From the foregoing description taken in connection with the accompanying drawings, it is thought the complete construction and the uses and advantages of the invention will be clear to those skilled in the art.

What I claim is:

1. In combination with a keg and its head and the hoop that embraces the staves adjacent the head; of a head retaining member including a strap lying across the outside face of the head and terminating in hooked portions that engage over the ends of the staves and project down between the staves and the hoop, the ends of which strap member being bent up over the hoop to be retained in place thereby.

2. In combination with a keg having a head and a hoop encircling the keg adjacent to the head; of a head retaining device consisting of a pair of strap members adapted to lie across and engage the outside face of the head, means for securing said strap members together in crossed relation, the ends of said strap members being hooked over the end of the keg and passed down between the keg and the hoop, said strap members having their extremities bent up over the hoop to be retained thereby.

3. As a new article of manufacture, a head securing device comprising a pair of strap members, one of which is provided with tongues and the other with slots, the tongues of one of the members passing through the slots of and being clenched over the other member to secure said members together in crossed relation, said members having hook ends to fit over the end of a keg and terminating in portions adapted to be located between the keg body and the hoop at the head end of the keg and adapted to be bent back over the hoop for securing purposes, said strap members adapted to lie on the outside face of the head whereby the same may be applied to the keg after the head is in place.

CHARLES FRANCIS LOFE.
